US00D591258S

(12) **United States Design Patent**
Wilson

(10) **Patent No.:** **US D591,258 S**
(45) **Date of Patent:** **** Apr. 28, 2009**

(54) **CELLULAR PHONE AND MULTIMEDIA DEVICE**

(76) Inventor: **Keith H. Wilson**, 946 Jerome St., Brooklyn, NY (US) 11207

(**) Term: **14 Years**

(21) Appl. No.: **29/317,552**

(22) Filed: **May 1, 2008**

(51) **LOC (9) Cl.** **14-03**

(52) **U.S. Cl.** ..... **D14/138 AB**; D14/345; D14/346; D14/203.4

(58) **Field of Classification Search** ..... D14/138 AB, D14/496, 203.1–203.7, 341–347; 455/575.3
See application file for complete search history.
